(Continued)

Primary Examiner — Catherine A Tuttle(74) *Attorney, Agent, or Firm* — Ryan Kromholz & Manion, S.C.(57) **CLAIM**

The ornamental design for a baseball, as shown and described.

DESCRIPTION

FIG. 1 is a right side view of a baseball;
 FIG. 2 is a left side view of the baseball of FIG. 1;
 FIG. 3 is a front side view of the baseball of FIG. 1;
 FIG. 4 is a back side of the baseball of FIG. 1;
 FIG. 5 is a top side of the baseball of FIG. 1; and,
 FIG. 6 is a bottom side of the baseball of FIG. 1.
 The broken lines are included for the purpose of illustrating the elements of the ball that form no part of the claimed design.
